FACING BAND

Isadore D. Wolfson, New York, N. Y.

Application June 28, 1938, Serial No. 216,277

2 Claims. (Cl. 139—387)

This invention relates to improved adjustable bands and band blanks, particularly bands and band blanks made of textile fabric.

Adjustable bands are commonly employed in articles of wearing apparel where it is desirable to adjust or vary the size of an article. Thus bands of this character are employed in the neckbands of ties, as taught in my Patent No. 1,486,822 and are also employed in suspenders and garters.

It is an object of the invention to provide an improved band of the above character which can be readily adjusted to the desired size or length and which is of improved reinforced construction so that the portion of the band which is subject to the greatest strains and stresses is of the strongest construction.

A further object is to provide a band of the above character which is of improved appearance and which conceals the head of the fastening means and protects the body of the wearer from contact therewith.

For a fuller understanding of the invention reference should be had to the accompanying drawing, in which

Fig. 1 is a perspective view of a band embodying my invention, showing one embodiment thereof;

Fig. 2 is a plan view of a band blank embodying my invention;

Fig. 3 is a cross-sectional view through the band, in the direction of the arrows on the line 3—3 of Fig. 1;

Fig. 4 is an enlarged detailed view of the inner surface of one of the plies of the band;

Fig. 5 is an enlarged detailed view, similar to Fig. 4, of the opposite side or outer surface of the ply of the band;

Fig. 6 is an enlarged cross-sectional view through the ply of the band shown in Figs. 4 and 5;

Fig. 7 is a longitudinal sectional view in the direction of the arrows on the line 7—7 of Fig. 1;

Fig. 8 is a view of a band blank embodying my invention, showing one manner of folding it to form a convenient commercial package;

Fig. 9 is a cross-sectional view of a modified form of my invention formed of a single ply of material.

The preferred form of my invention consists of a relatively narrow and elongated band 10 formed of a plurality of layers of woven textile fabric such as silk, cotton or synthetic rayon integrally joined along their longitudinal edges.

The band is preferably woven in tubular form as

shown most clearly in Figs. 1, 3 and 7, so as to provide two superimposed layers 11 and 12 having beaded longitudinal edges 14.

In manufacturing the band a relatively long blank or strip such as indicated at 15 in Figs. 2 and 8 may be woven. The ends of the individual bands may be indicated on the blank by means of tapering lines of tracing stitches 16 woven into the blank. In packing or shipping the blank it may be folded at the end of each line of tracing stitches 16 in zigzag fashion as shown in Fig. 8. When it is desired to use the individual bands the blank may be conveniently severed into band lengths by cutting at the end of each line of tracing stitches and the individual band may then be finished with a tapered end corresponding in shape to the line of stitches.

As previously stated, the band is preferably formed of two plies of material. One ply 12, may be woven in the usual manner in a plain fabric or a Jacquard design. The other ply, 11, however, is preferably provided with a plurality of slots or elongated openings 17 woven in the fabric and provided with selavage edges as shown. The lateral edges of ply 11 are of plain warp and weft weaving as indicated at 18 in Figs. 4 and 5. However, the central portion of ply 11 adjacent the woven openings 17 is provided with a longitudinally extending reinforcing zone which is preferably formed of a plurality of reinforcing warp threads 19 woven into the fabric at this point. The additional reinforcing warp threads are preferably parallel to each other and parallel to the regular warp threads of the band so as to extend longitudinally of the band as shown.

In the area between the successive openings 17 the reinforcing warp threads 19 are exposed on the outer surface of the ply 11 to a greater degree than on the inner surface as indicated at 20 in Fig. 5. The reinforcing warps 19 through this intermediate area extend through the fabric to the inner surface of ply 11 only at spaced intervals and for relatively short distances as shown at 21 in Fig. 4. In the area immediately surrounding the openings 17 the reinforcing warp yarns are preferably woven through the fabric so as to be exposed to a substantially equal degree on both surfaces of ply 11 in the manner indicated at 22 in Figs. 4, 5 and 6. Thus it will be seen that the entire central portion of ply 11 of the band is provided with a reinforced zone which extends through the portion of the band that is subjected to the greatest strains and stresses. Immediately around each opening the reinforcing threads are woven through the

fabric in regular fashion and are extended around the selvage edges thereof so as to afford additional protection to the edges of the openings through which the fastening means are projected.

5 While I prefer to form my improved band of a plurality of layers of fabric, preferably two layers as shown, I may nevertheless form it of a single fabric as shown at 23 in Fig. 9. The band 23 is woven from textile fabric such as silk, cotton, linen or synthetic materials and is similar in all respects to layer or ply 11 of band 10 with the exception that it is formed with selvage edges along its lateral edges 24. Thus the band 15 23 is formed of a plurality of openings 17 corresponding to the openings 17 in the first form of my invention and is formed with a longitudinally extending reinforcing area similar to the reinforcing area indicated at 19 in the first form 20 of my invention.

As previously stated, my adjusting band may be used for many different purposes. Thus it may be used in the neckband of a tie, as taught in my Patent No. 1,486,822 or as part of a garter 25 or suspender. In using my band it may be applied and attached as shown in Figs. 1 and 7, in which the band has connected to the end thereof a small metal fastener 25 having an arcuate head 26 adapted to be projected through any one of the openings 17. The band is extended through a metal adjusting loop 27 supported at the end of a fabric strip 28. It will be appreciated that the relative length of the band 10 may be adjusted by shifting the band through 30 the loop 27 and that the band may be releasably held in any adjusted position by projecting the head 26 through the adjacent opening 17. When the head 26 is thus projected through the opening 17 it will lie flatly in position and cannot be accidentally released. It will be appreciated however, that the fastener can be released from the opening 17 when desired, by a relatively simple manipulation.

When a tubular or multiple-ply type of band 45 is employed in accordance with the preferred form of my invention it will be appreciated that the fastener will not be visible from the surface of the band on which the ply 12 is formed and that if the ply 12 is placed against the body of

the wearer it shields or protects the wearer from contact with the fastener. It will also be appreciated that due to the provision of the beaded edges in the preferred form of my invention the several plies of the band will assume a flat 5 position as shown.

So as to facilitate the proper adjustment of the band, numerals or other indicia may be woven into the reinforcing zone adjacent the openings 17 as indicated at 29. It will also be appreciated that ornamental designs and words, names, or the like may be woven directly into the fabric. As previously stated, the band may be woven of any textile yarn such as cotton, silk or synthetic yarns. It may also be woven of 10 Lastex or similar elastic or rubber yarns in which 15 case the thread may be disposed on the bias.

It should be appreciated of course, that modifications may be made in the illustrated and described embodiments of my invention without departing from the invention as set forth in 20 the accompanying claims.

I claim:

1. An adjustable facing band comprising a pair of superimposed plies formed of woven textile fabric and having integrally connected longitudinally extending beaded edges, one only of the plies having a plurality of spaced openings having woven selvage edges formed therein in a row adjacent the center of the ply, and said ply being also formed with a longitudinally extending centrally disposed reinforcing zone extending substantially from end to end of the band, said reinforcing zone being formed so as to surround the central openings and being woven of 30 yarns disposed in parallel relationship extending longitudinally of the band and independent of the yarns forming the body of the band.

2. An adjustable facing band as set forth in claim 1, in which the yarns forming the reinforcing zone are exposed to a greater degree on the one surface of the ply than on the other surface of the said ply in the portions of the reinforcing zone intermediate the openings, and in the portions of the reinforcing zone surrounding the openings the said yarns forming the reinforcing zone are exposed on both surfaces of the 40 ply to a substantially uniform degree.

ISADORE D. WOLFSON.
